VALVE TAPPET

Arthur Burton Buckley, Carshalton, England

Application April 12, 1943, Serial No. 482,815
In Great Britain March 9, 1942

9 Claims. (Cl. 123—90)

This invention relates to tappets of the type (hereinafter referred to as the type described) comprising male and female telescopic members that define an internal chamber of variable size adapted to contain a liquid and are movable one in relation to the other for determining the length of the tappet, provision being made for permitting a restricted escape of liquid from the internal chamber along a leakage path.

In tappets of the type described proposed heretofore, the restricted escape of liquid from the internal chamber has been so small as to be negligible in so far as interference with the operation of the tappets was concerned. In one such construction that comprised a tappet body in which a piston was slideable, and that contained a reservoir for liquid and a valve device controlling communication between it and a pressure chamber in the tappet body, the restricted flow of liquid set up (when the device was in operation) a small constant circulation of the liquid in a closed circuit from the pressure chamber at one side of the piston to a space, constituting a reservoir for oil in the body, at the other side of the piston. In this proposed earlier construction the arrangement was such that communication between an external source of supply under pressure was established with the interior of the tappet only at the moment of closure of the engine valve controlled by the tappet for the purpose of replenishing oil that had leaked away.

It is an object of the present invention to control the operation of a tappet of the type described in an improved manner.

Another object is to provide an improved construction of tappet of the type described which shall be self-priming.

A further object is to provide a "non-atmospheric" tappet of the type described for ensuring that air shall not collect in the tappet, and be readily expelled should this happen.

According to a feature of the invention there is provided a tappet of the type described wherein the telescopic members define a pressure chamber of variable size adapted to contain a liquid, a restricted escape of liquid from the pressure chamber being permitted, which tappet is characterised in that provision is made for controlling and adjusting the restricted leakage from the pressure chamber independently of the fit of the piston in the body, and thereby controlling the operation of the tappet.

When a tappet as set forth above is combined with a fixed tappet guide member, and liquid-supply means arranged to supply liquid from an

external source of supply under pressure by way of the guide member to the pressure chamber for elongating the tappet, the leakage-control means may be associated with the liquid-supply means.

The leakage-control means may comprise a valve device that is associated with means for supplying liquid under pressure to the pressure chamber.

10 When the tappet guide member has an inlet port for supplying liquid under pressure to the pressure chamber for elongating the tappet, according to another feature of the invention packing means is situated at opposite sides of said port for preventing liquid from escaping to atmosphere at the ends of the tappet by way of the joint between the tappet and the guide member. Such a tappet has the advantage of being self-priming.

20 Preferably the packing means is disposed so as to permit the escape into the atmosphere of air from within the tappet by way of said joint, and at the same time to cause the return of a substantial proportion of the tappet leakage to a liquid-supply conduit, which arrangement has the advantage that the liquid consumption is reduced to a minimum with the corresponding advantage that the risk of the admission of air or other impurities is greatly reduced. A tappet having such packing means may be described as a "non-atmospheric" tappet.

25 Preferably provision is made for accommodating in the liquid-supply means that quantity of liquid which is displaced from the tappet due to its contraction, and for regulating any excessive fluid pressure which may tend to be set up in the liquid-supply means due to that accommodation.

30 A preferably pneumatic pressure-absorbing device may be provided for relieving any excessive fluid pressure that is set up or tends to be set up in the liquid-supply conduit due to the injection of liquid from a tappet due to its contraction.

40 45 This pressure-absorbing device may be situated externally of the tappet in connection with a conduit for the supply of liquid under pressure to the tappet.

50 Limiting means, preferably of the pin-and-slot type, may be arranged in the tappet for automatically limiting the endwise movement of its telescopic members one in relation to the other.

Other features of the invention relate to various constructions and arrangements of leakage-control means for permitting a restricted leakage

of liquid from the pressure chamber, and to priming means for the liquid-supply means.

One embodiment of the invention and modifications thereof are diagrammatically illustrated by way of example in the accompanying drawings, wherein:

Figure 1 shows one construction of tappet partly in longitudinal section having an internal valve device, together with an oil-supply system, shown partly in section and partly broken away, for supplying oil to the tappet, and

Figure 2 shows a modified construction of tappet, partly in longitudinal section, also having an internal valve device;

Figure 3 is a vertical section showing another modified construction of tappet according to the invention having an external valve device,

Figure 4 is a detail view of the valve member removed from the tappet, and

Figure 5 is a diagram illustrating an oil-supply system for supplying a plurality of tappets as shown in Figure 3;

Figures 6 and 7 are longitudinal sections showing constructions of tappets according to the invention having external valve devices, and

Figure 8 is a transverse section taken on the line 8—8 in Figure 7, and

Figure 9 is a detail view of the valve member removed from the tappet shown in Figure 6.

Like reference characters designate like parts throughout the several views.

Referring first to the tappet assembly shown in Figure 1, a tappet, designated generally 20 is movable endwise in a fixed tappet guide 22, and comprises two hollow, cylindrical, telescopic, male and female members 24, 26, that enclose between them a main chamber, described herein-after, of variable volumetric capacity for containing liquid, hereinafter referred to as oil. The telescopic member 24 is a female member that constitutes the tappet body, hereinafter referred to as the body, and is formed as a cylinder 28 at one end, with a stem 30 at its opposite end, which stem has a foot 32 for bearing against a cam 34 on a cam shaft 35 for operating the valve gear of an engine with which the tappet is associated. The telescopic member 26 is a male member and constitutes a two-diameter piston 36, 38 having an inner part 36 movable axially in the cylinder 28, and an outer part 38 movable axially in the tappet guide 22, which outer part 38 has at its outer end a suitably-shaped external face 40 to bear against the tip of a stem 42 of an engine valve, or against some other member of the valve gear. Obviously, if desired, the male member 26 may co-act with the cam 34, and the female member 24 with the valve stem 42 or other part of the valve gear.

The female member 24 has an axial bore comprising an internal chamber 44 that has an annular conical valve seat 46 at one end, and has its other end in open communication with the adjacent inner end of a cylindrical space 48 in the cylinder 28 by way of peripheral holes 50 in a plate or washer 52 that is also perforated centrally, and may be held in any convenient manner in the female member 24 at the inner end of the cylinder 28. As shown, this plate 52 is a press fit in the female member, and lies against a shoulder 54 formed therein. The end portion of the said bore remote from the cylinder 28 forms a relatively small cylindrical space 54 that opens at one end into the inner end of the chamber 44, and at its other end into the inner end of a radial oil-inlet hole 58.

The main chamber aforesaid in the tappet comprises the chamber 44, space 48 and hole 50, which together constitute a pressure chamber of variable volumetric capacity, and the space 56 and hole 58, which together form an ante-chamber situated at the inner end of the said pressure chamber 44, 48, 50.

An internal valve device comprises a spring-loaded valve member in the form of a ball 60 which is pressed against its seat 46 by one end of a valve spring 62, whereof the other end bears against the plate 54. This valve member 60 is situated at the junction of the pressure chamber and ante-chamber, and permits a one-way flow of oil from the ante-chamber 56, 58 to the pressure chamber 44, 50, 48. When this valve device is closed, and the fluid pressure in the pressure chamber is greater than that in the ante-chamber, restricted leakage of oil can take place from the pressure chamber along a leakage path, the amount of which leakage can be controlled and regulated as described hereinafter.

The tappet guide 22 has a lateral port 64 for the admission of oil into the tappet 20 from an external oil-supply system described hereinafter. The inner end of the female member 24 has an external annular groove 66, hereinafter referred to as an oil belt, which in all positions of the tappet is in open communication with the oil-supply port 64, and has one end in open communication with the radial hole 58 forming part of the said ante-chamber. The other end of the oil belt 66 is connected by a longitudinal groove 68, formed in the outside of the cylinder 28, with an annular space 70. This space is bounded within the tappet-guide 22 at one end by a shoulder 72 formed at the junction of the two parts 36, 38 of the piston, and at the other end by an end face 74 of the cylinder 28. This end portion of the cylinder may be internally chamfered, as shown at 76. The said leakage path from the pressure chamber 44, 50, 48 is formed by the joint 77 between the cylinder 28 and part 36 of the piston, annular space 70, groove 68 and oil-belt 66, which is in open relation with the ante-chamber 56, 58. Leakage control means described herein-after, that is independent of the fit of the piston in the body of the tappet, is provided for varying the amount of restricted leakage along said path.

Connecting means for connecting the ante-chamber 56, 58 with an external oil-supply pipe 78, hereinafter referred to as an oil gallery, comprises the said port 64, and the said oil belt 66, thus ensuring a constant supply of oil under pressure to the ante-chamber 56, 58.

Packing means is provided for rendering oil-tight the joint between the tappet 20 and its guide 22, at opposite sides of the oil-supply connecting means, which packing means, while preventing escape of oil, does permit the escape of any air that may tend to collect in the tappet and its oil-belt. As shown, this packing means comprises two packing rings 80, 82, each in the form of a piston ring provided, respectively, in a groove 84 in the female member 24, and in a groove 86 in the part 38 of larger diameter of the male member 26. These grooves 84, 86 and their packing rings 80, 82 lie in spaced relation away from the opposite ends of the oil belt 66 and the annular space 70 connected therewith. By this means oil can be delivered to the tappet without substantial loss while permitting the tappet to function under the action of the oil pressure and the influence of the cam 34.

Limiting means may be provided for mechani-

cally limiting the elongation of the tappet. This limiting means may comprise a radial pin which enters a radial slot that is formed in the male member in the portion where it engages the female member, each end of said pin also engaging corresponding holes in the female member, the elongation of the tappet being governed by the length of said slot in the male member. As shown, the smaller part 36 of the piston is provided with a limiting slot 88 which houses a stop pin 90 that enters holes in the tappet body.

When performing the function for which the tappet is provided, namely, to transmit the power of the cam 34 to the member 42 of the valve gear while at the same time maintaining its own correct length, the tappet 20 operates as follows:

Under the lifting pressure of the cam 34 restricted oil leakage, hereinafter referred to as piston leakage, takes place from the pressure chamber 44 through a very narrow annular space at the joint 77 between the inner periphery of the cylinder 28 and the adjacent cylindrical face of the piston 36, owing to the absence of an hermetic oil seal between these two parts. This piston leakage flows into the oil belt 66 which is in connection with the oil gallery of the engine with which the tappet is working, so that the oil in the oil belt 66 is at gallery pressure. Also a certain amount of oil leakage, hereinafter referred to as packing leakage, will take place from the oil system which supplies the tappets with oil in spite of the packing arrangements provided to minimise it, and the volume thus ejected in combination with the aforesaid packing leakage, provides the total restricted leakage aimed at, referred to herein as tappet leakage. The oil ejected from the pressure chamber flows into the oil gallery against gallery pressure. Since oil at normal pressures and temperatures is incompressible, this tappet leakage must be accommodated in some appropriate space, or be otherwise disposed of, and it may profitably be used to supply one of the other tappets of the same engine, whose demand for oil synchronises therewith. Part of a second tappet that is associated with the same engine and is connected to the oil gallery 78, is diagrammatically shown at 220. This synchronism exists to a very marked degree in many engines, in which these tappets are conveniently employed, but to ensure the best conditions of operation a pressure-absorbing device, designated generally 96, may be incorporated in the oil-supply system comprising the oil gallery 78.

As shown, this pressure-absorbing device 96 is situated externally of the tappet guide 22, in open communication with the oil gallery 78 for the supply of oil under pressure to the tappet 20 and other tappets associated with the same engine. It comprises a cylindrical vertical vessel 98, whereof the upper portion is hermetically closed and filled with air, and its lower portion is connected by a branch pipe 100 with the oil gallery 78 that opens by way of the port 64 into each tappet guide 22. This lower portion of the vessel 98 is filled with oil from the oil gallery 78, to which an oil pump, not shown, can be connected at a tubular connection 102 by way of a check valve 104 comprising a non-return valve member 106 constituted by a ball that controls communication between the branch pipe 102 and a short tubular branch 108 connected to the oil gallery. Since the oil in this vessel 98 is in direct communication with the oil gallery, any variations

in pressure in the latter that tend to be set up due to excess or deficit of oil arising from the variations of the tappet demand, are equalised by the resilience of the air compressed above the oil in the vessel 98, whereby violent changes in gallery pressure are avoided.

Control and regulating means for controlling the restricted tappet leakage comprises a spring-controlled relief valve 110 arranged in direct communication with the oil gallery 78. This relief valve has a duct 112 that opens at one end into the tubular branch 108, and has its other end controlled by a valve member in the form of a ball 114 that is loaded by a coil spring 116, and controls communication of the duct 112 with a tubular branch 118 that opens to atmosphere, and may deliver any escaping oil to the engine sump when the spring 116 permits of such escape. A set-screw 119 is provided for accurately adjusting the pressure of the spring 116 on the ball 114, and thereby regulating the tappet leakage. In this connection it may be pointed out that the leakage from the pressure chamber within the tappet is opposed by the fluid pressure of the oil outside the tappet, i. e., the oil-gallery fluid pressure, and this in turn is governed by the packing means constituted by the piston rings 80, 82.

In the interval during which the above-mentioned operations have been taking place, the cam 34 has continued to revolve, the engine valve associated with the tappet 20 has closed, and at that instant the tappet 20 finds itself shorter than it was by an amount determined by the cubic contents of the tappet leakage before it left the pressure chamber. The tappet being now no longer under the action of the pressure of the engine valve-spring, is free to elongate and it does so under the gallery pressure of the oil, which, by way of the connecting means 64, 66 and the ante-chamber 58, 56, gives access to the pressure chamber 44, thereby driving the male member 26 in the direction away from the female member 24, which elongation of the tappet will be arrested by the outer face 49 of the male member abutting against the valve spindle 42 of the valve gear, or as otherwise provided by the limiting means 88, 90.

In the foregoing description it has been assumed that during the interval when the tappet 20 has been functioning in the manner described, no alteration has taken place in any of the component parts of the valve mechanism, except in the tappet itself. Assuming, for example, that during that interval one of the components, e. g., the engine valve stem, has lengthened under the heat of the engine, then the amount of expansion of the tappet will be reduced by a corresponding amount. For example, assuming that the tappet leakage has shortened the tappet by six thousandths of an inch, and that the valve stem has lengthened by one thousandth (a very exaggerated figure) then the tappet will elongate by five thousandths so as to maintain its correct length. If, on the other hand, the valve stem has shortened by a corresponding or other amount within the range of the tappet, then the tappet will elongate by an amount equal to the hypothetical six thousandths of an inch plus the amount by which the engine valve stem has shortened. The exception to this routine is when the engine valve gets hung up in its guides; in that case the elongation of the tappet is limited to the range permitted by the limiting means 88, 90.

It frequently happens that when the above conditions occur, the vibrations of the engine free

the held-up valve which, after liberation, continues to function as before. In the event of this happening in an engine equipped with tappets 20 as described above, the pressure of the engine valve spring induces a leakage of oil from the pressure chamber 44 until the tappet has assumed its correct length. The amount of this leakage is, however, out of all proportion to the demand of any of the adjacent tappets, so that the relief valve 110 comes into operation and discharges the surplus to the engine sump or as may otherwise have been arranged.

To assist the starting of the engine an air-vessel 120 in the form of a pressure tank is incorporated in the oil-supply system and is provided with a non-return inlet valve 122 comprising a valve member 124 in the form of a ball which permits flow of oil into the tank, but prevents flow in the opposite direction into the oil gallery 78, to which the inlet valve 122 is connected by a branch pipe 126. When the engine is in operation, air above the oil in this tank 120 is necessarily kept at the maximum pressure reached by the gallery pressure, owing to the provision of its non-return valve 122, so that a reserve of compressed air is always available for engine starting, if actuating means are provided for making this reserve available if required.

These actuating means may comprise an outlet cock designated generally 128 having an operating lever 130, which may be hand-operated, to release oil under air pressure when the engine is started. Alternatively, as shown, the cock may be in mechanical connection, as by a spring 132, with the electric started knob or push button of the engine to come into operation simultaneously with the starter motor and to be cut out with it. In either case, when the lever 130 is moved from its normal rest position, shown in full lines, to its starting position, shown in broken lines, a spigot-like member 134 of the cock having a flat face 136, on which rests a pusher member 138, lifts the ball 124, and permits the compressed air in the tank 120 to force oil out of the tank by way of an annular space, surrounding the member 134, into the oil-supply system and towards the tappet. Any oil which has then been ejected from the pressure tank 120 during the engine-starting operation will subsequently be forced back into the same tank by the rising gallery pressure, and will be available to be drawn upon as occasion arises. Since the pressure tank 120 is hermetically sealed, and the non-return valve device 122 and cock 128 are of simple construction and not liable to leak, the tank 120 will remain under pressure for an indefinite time and be always available to fulfil the purpose for which it has been installed.

It will be appreciated from the above that elongation of the tappet is effected by the pressure of an external supply of oil used for enlarging the cubic contents of the main chamber of the tappet, without depending on any spring for moving the piston and body of the tappet relatively one to the other. Provision is made for accommodating in the oil-supply system any oil displaced from the main chamber due to its contraction, and also for relieving excessive oil pressure that is set up, or tends to be set up, in the tappet due to its contraction. It will also be appreciated that the valve-gear comprising one or more valve-gear units including a spring-loaded engine-valve and a self-adjusting, non-

atmospheric tappet operating to be self-adjusting as to its length and to dissipate power thereby, is provided with means for storing said dissipated power pending its restoration to the tappet during its period of idleness, as by means of the air vessel 120 connected with the oil system supplying the tappet. The term "non-atmospheric tappet" refers to one in which the pressure chamber and ante-chamber in the tappet are shut off from the atmosphere during the operation of the tappet.

Referring now to Figure 2 showing a modified construction of tappet designated generally 140, movable in a fixed tappet guide 142, this tappet also comprises two hollow, cylindrical, telescopic, male and female members 144, 146 that enclose between them a main chamber of variable volumetric capacity for containing oil. The telescopic member 146 is a female member that constitutes the tappet body, and is formed as a cylinder 148 at one end, and with a stem 150 at its opposite end, which stem bears against the tip of a stem 42 of an engine valve, or against some other member of the valve-gear. The male telescopic member 144 is a two-diameter piston 152, 154, whereof the inner part is movable axially in the cylinder 148, and the outer part 152, is movable axially in the tappet guide 142, which outer part 152 has a foot 156 for bearing against a cam 34 for operating the valve-gear comprising a valve having the stem 42. If desired, the female member 146 may co-act with the cam 34, and the male member 144 with the valve stem 42 or other part of the valve gear. A chamber in the hollow part 154 of the piston 144 contains a spring 160 and has at its inner end a radial port 162 leading to the joint where the male and female members loosely mate. The spring 160 bears at its outer end against an abutment in the form of a plate 164 that is seated on the inner end of the cylinder 148 and has apertures 166 which place the chamber 158 in the cylinder 154 in open communication with a three-diameter chamber 168, 169, 170 in the stem 150 of the female member 146. A valve member 172 in the form of a ball has a seat 174 at the junction of the two chambers 169 and 170, which ball is under the action of gravity and, when permitted by the fluid pressure in the tappet to do so, can rest on the plate 164 and place the chamber 170 in open communication with the chamber 158 in the cylinder 154. This chamber 170 is connected by a radial inlet hole 176 to the outside face of the female member at the inner peripheral face 178 of the tappet guide. The chamber 158 in the cylinder and the chambers 168, 169 in its stem together with the holes 166 in the plate 164 constitute a pressure chamber corresponding to the pressure chamber 44, 50, 48 described above with reference to Figure 1, while the chamber 170 and radial hole 176 constitute an ante-chamber corresponding to the ante-chamber 56, 58 described above with reference to Figure 1.

The tappet guide 142 has a lateral port 180 for the admission of oil into the tappet 140 from an external oil-supply system similar to that described above, and the female member 146 has an external annular groove 182, hereinafter referred to as an oil belt, which corresponds to the oil belt 66 also described above with reference to Figure 1, and in all positions of the tappet is in open communication with the oil-supply port 180. This oil belt 182 has one end in open communication with the inlet hole 176 forming part

of the ante-chamber. The other end of the oil belt is connected by a longitudinal groove 184 formed in the outside of the cylinder 148, with an annular space 186. This space 186 corresponds to the annular space 70 described above with reference to Figure 1 formed between a shoulder 188 at the junction of the two parts 152, 154 of the piston, and by an end face 190 of the cylinder 148.

In this tappet 140 a leakage path from the pressure chamber is formed by the radial port 162, the joint between the two telescopic members, groove 184 and oil belt 182, which is always in open relation with the port 180 connected to the oil-supply system.

Leakage control means that is independent of the fit of the piston in the body of the tappet, is provided in the oil-supply system, as described above with reference to Figure 1, for varying the amount of restricted leakage along said path. Also, packing means in the form of two packing rings 80, 82, similar to those described above with reference to Figure 1, are provided respectively in the female member 146 and the male member 144. In addition, limiting means 88, 90, similar to those described above with reference to Figure 1 are associated with the part 154 of the piston of smaller diameter.

This tappet is intended to operate in a substantially horizontal position, for example with its longitudinal axis, indicated at 192, lying at an angle to the horizontal plane, indicated at 194, so as to place the male member at a higher level than the female member.

The operation of this tappet 140 and the oil-supply system to which it is connected is similar to that of the tappet 20 and its oil-supply system described above with reference to Figure 1, but differs therefrom in that the spring 160 assists the fluid-pressure in the pressure chamber in elongating the tappet, so that elongation of the tappet is not dependent solely on the gallery pressure. In addition, the ball valve 80 which closes under the action of gravity, is not seated under the action of a valve spring, but under the action of fluid-pressure in the pressure chamber when the fluid-pressure in that chamber is greater than the fluid-pressure in the ante-chamber during the contraction of the tappet.

Referring now to Figures 3 to 5, a plurality of modified constructions of tappets, designated generally 200, are connected to an oil-supply system comprising an oil gallery 78, check valve 104, relief valve 110, and pressure-absorbing device 96 as described above with reference to Figure 1. As clearly shown in Figure 3, each tappet 200 comprises two hollow, cylindrical, telescopic members 202, 204 that enclose between them a pressure chamber 206 of variable volumetric capacity. One member 202 is a female member constituting the tappet body, and comprises a cylinder 208 and a stem 210. The other telescopic member 204 is a male member constituting a two-diameter piston, whereof a part 212 of smaller diameter is slidably endwise in the cylinder 208 and carries a short piston-rod 216, and a part 214 of larger diameter is slidably in a fixed tappet guide 218 that is integral with the cylinder block of the engine with which the tappet is associated. The piston-rod 216, that bears against the valve stem 42 which is under the action of a valve spring 219, is provided with limiting means 88, 90 as described above with reference to Figure 1 for mechanically limiting the elongation of the tappet.

The female member 202 has an external annular groove 222 that surrounds the cylinder 208 and constitutes an oil belt which is connected at one end by way of one or more radial holes 224 with the pressure chamber 206. This pressure chamber is connected by a longitudinal groove 226, formed in the part 212 of the piston, with an annular space 186, similar to that described above with reference to Figure 2, situated between the inner end face 190 of the cylinder and a shoulder 188 of the piston. Packing means in the form of piston rings 84 and 86, similar to those described above with reference to Figure 1, are provided respectively in the female member 202 and the male member 204 at opposite ends of the oil belt 222. The tappet guide 218 has at 228 an annular groove constituting an inlet that opens at its inner periphery through the internal cylindrical face 230, against which the tappet 20 is movable, and at its outer periphery into the inner end of an oil duct 232, constituting a filling inlet hole, which is in open communication between its ends with the gallery 78 and is normally closed at its outer end by a grub screw 233. As described so far this tappet is similar to that described above with reference to Figure 1, but differs therefrom in that no valve device is provided within it.

An oil inlet-valve member 229 in the form of a 30 detachable arcuate leaf spring is accommodated in the groove 228 and controls the supply of oil to the pressure chamber. This valve member 229 has near one end a stop pin 231 which lies in a recess 233 formed in the tappet guide to receive 35 it at a situation diametrically opposite to the inlet duct 232. The width of the groove 228 is greater than the diameter of the duct 232, and the width of the valve member 229 is less than that of the groove 228, so that when the valve member 229 is unseated at the duct 232 oil can 40 flow round it to the oil belt 222.

In order to relieve any excessive fluid-pressure that may be set up in the pressure chamber 206, the ports 224 and longitudinal groove 226 of the oil belt 222, and the annular space 186 connected with the groove 222 together constituting a main chamber in the tappet, leakage means comprising a non-return relief or safety valve is provided outside the tappet for permitting a restricted escape of oil from the pressure chamber. This relief valve, designated generally 234, comprises a nut-equipped casing 236 that is secured in a cylindrical hole 238 in the tappet guide 218 that opens at its inner end by way of a port 240 through the cylindrical face 230 of a bore hole containing the tappet. The inner end of the hole 238 provides at 242 a conical seat for a valve member 244 in the form of a ball, which seat is situated opposite a second conical seat 243 formed on the inner end of the casing 236. A spring 246 bears at one end against this ball, and tends to seat it on the seat 242; the spring bears at its other end against an abutment 248 in the form of a set-screw that is adjustable in the valve casing 236 and can be secured in its adjusted position by a lock-nut 250, whereby the pressure of the spring on the ball 244 can be adjusted. The valve casing 236 has a lateral port 252 in open communication with the oil inlet hole 232 by way of the liquid-supply conduit constituted by the oil gallery 78 situated in the tappet guide 218.

The fluid pressure in the oil gallery always tends to open the resilient valve member 229 and, together with the spring 246, tends to seat the ball 75 244 on its seat 242. The lift of the cam 34 is so

great as to place the port 240 in open relation with the annular space 186 in the tappet once each revolution of the cam. The oil in this annular space is always at the same pressure as that of the oil in the pressure chamber 206, so that if this pressure is excessive a restricted escape of leakage oil from the pressure chamber can take place when the cam 34 is at or near the top of its stroke, which leakage can be controlled and adjusted by means of the screw 248. The leakage oil that flows past the ball 244 and is ejected from the aforesaid relief or safety valve 234 when the ball moves from the seat 242 to the seat 243, flows into the oil gallery 78 against gallery fluid pressure.

It will be appreciated from the above that in the construction of tappet shown in Figure 3, the leakage which occurs through the relief valve 234 depends principally on the oil pressure and strength of the relief valve spring 246 and is therefore independent of the fit of the piston 204 in the tappet body 202; it is also independent of the temperature of the oil except in so far as the flow of oil through the relatively large passages through which it passes is affected by the temperature to a small extent, but the effect produced on the operation of the tappet by temperature variations is much less than in the constructions described above with reference to Figures 1 and 2.

On the other hand, in the construction of tappet shown in Figure 3, should any leakage occur past the packing rings 84, 86 it will influence the operation of the tappet, but its effect will be analogous to that produced by the piston leakage in the constructions shown in Figures 1 and 2, but there is this difference, namely that the leakage past the packing rings 84, 86 is susceptible of being prevented by the resilient nature of the packing means, whilst when the leakage path comprises the joint between the adjacent faces of the male and female members no such compensating effect is possible.

Moreover, in the construction shown in Figure 3, the rate of tappet leakage, which plays a very important part in the operation of the tappet, is adjustable at any time by means of the relief valve 234, whilst in the constructions shown in Figures 1 and 2 the piston leakage is fixed once for all when the parts are manufactured, although it is susceptible of adjustment by the means described above. Further, in the construction shown in Figure 3 leakage over and above any packing-ring leakage that may take place, occurs only at the top of the tappet stroke, whereas in the constructions shown in Figures 1 and 2 it continues for the whole of the stroke.

Referring now to Figure 6, a tappet, designated generally 260, is provided with a combined tappet inlet-valve and tappet relief-valve, as described hereinafter, that has a valve-member common to them both, and is provided with means for adjusting its lift to regulate the tappet leakage. This tappet 260 movable in a fixed tappet guide 262 comprises two hollow, cylindrical, telescopic members 264, 266 that enclose between them a pressure chamber 268 of variable volumetric capacity. The member 264 is a female member constituting the tappet body, and comprises a cylinder 270 and a stem 272. The other telescopic member 266 is a male member constituting a two-diameter piston, whereof a part 274 of smaller diameter is slidably endwise in the cylinder 270, and a part 276 of larger diameter is slidable in the internal cylindrical face 278 of the bore hole in the tappet guide 262 which is

integral with the cylinder block of the engine with which the tappet is associated. The piston 274, 276 bears against the valve stem 42 controlled by a valve spring 219, and is provided with limiting means 88, 90, as described above with reference to Figure 1, for mechanically limiting the elongation of the tappet.

The female member 264 has an external annular groove 280 that surrounds the cylinder 270 and constitutes an oil belt which is connected at the inner end of the cylinder by way of one or more radial holes 282 with the pressure chamber 268. Additional radial holes 284 connecting the pressure chamber 268 with the oil belt are provided in the cylinder wall at a situation between its ends. A compression coil spring 286 that tends to elongate the tappet is accommodated in the cylinder 270 and bears against the inner end of the cylinder and the inner end of the part 274 of the piston. The length of the part 274 of the piston is preferably considerably shorter than the cylinder 270 and is made hollow up to a point where it intersects radial holes 287 connecting it with an annular space 186 at the end of the cylinder. A short part of a circulatory leakage path is provided at the joint 288 between these two parts 270, 274 of the tappet, which short part connects the pressure chamber 268 by way of the radial holes 287 and the annular space 186 with the annular groove 280. Grooves 290, 292 for preventing oil from escaping at the opposite ends of the tappet in the guide member 262 are provided respectively in the stem 272 of the female member 264, and in the larger part 276 of the piston. These grooves, which are preferably of semi-circular cross-section, even if not provided with piston rings or the like, constitute packing means for reducing the leakage of oil between the tappet and its guide at the ends of the tappet.

Connecting means for connecting the pressure chamber 268 with an external liquid-supply conduit, shown as an oil gallery 78 in the tappet guide 262, comprises a filling hole or port 294 that places the gallery 78 in open connection with the oil belt 280 in all positions of adjustment of the tappet. A combined tappet inlet-valve and tappet relief-valve, designated generally 296, having a valve member 298 in the form of a ball, controls the flow of oil through the inlet hole 294. This valve device 296 is constructed similarly to the valve device 234 shown in Figure 3, but differs therefrom in that only one valve seat 243 is provided, against which the ball can be seated by fluid pressure in the pressure chamber. When the fluid pressure in the gallery 78 combined with the pressure of the spring 286 is in excess of the fluid pressure in the pressure chamber, and the ball 298 is lifted from its seat 243, outward movement of the ball is arrested owing to its contacting with the periphery of the cylinder 270 in the oil belt, so that oil can flow into the pressure chamber. Should the pressure in the pressure chamber become excessive, however, the ball 298 will be returned to its seat 243, during which movement a restricted small amount of leakage can take place from the pressure chamber to the oil-supply system by way of the valve device 296 and the oil gallery 78. In this construction the amount of this leakage is adjustable according to the setting of the screw 248 which can vary the time taken for the ball 298 to move from one of its end positions to the other.

Referring now to Figures 7, 8 and 9, a tappet,

designated generally 300, is movable endwise in a two-diameter fixed tappet guide member 302, 304 which is distinct from a cylinder block 306 of the engine with which the tappet is associated. This tappet 300 comprises two hollow, cylindrical, telescopic male and female members 308, 310 that enclose between them a main chamber of variable volumetric capacity for containing oil. The telescopic member 308 is a female member that constitutes the tappet body, and is formed as a cylinder 312 at one end, and with a stem 314 at its opposite end, which stem bears against the stem 42 of an engine valve, or against some other member of the valve gear. The male telescopic member 310 is a two-diameter piston 316, 318, whereof the inner part 318 of smaller diameter is movable axially in the cylinder 312, and the outer part 316 of larger diameter has a foot 320 for bearing against the cam 34 for operating the valve gear. If desired, the arrangement may be reversed, and the female member may co-operate with the cam 34, and the male member with the valve stem 42. This tappet 300 comprises a pressure chamber 268, a coil spring 286 therein, a radial port 282, an oil belt 280, and an annular space 186, similar to the corresponding parts described above with reference to Figure 6. A reduction in the diameter of the part 318 of the piston forms an annular space 322 which is in open relation with the pressure chamber 268 by way of a radial port 324 at the inner end of the pressure chamber 268.

Connecting means for connecting the pressure chamber 268 with an external oil-supply system of the kind described above with reference to Figure 1, comprises two radial inlet holes 326 formed in the guide member 302 in such a position as always to be in register with the oil belt 280 in all positions of adjustment of the tappet. Externally the guide member 302 has an annular groove 328, into which the outer ends of these holes 326 open, which groove 328 is always in open communication with a liquid-supply conduit 330 constituting or connected to an oil gallery.

A combined tappet inlet-valve and tappet relief-valve in the form of a detachable arcuate leaf spring 332, shown detached in Figure 9, is accommodated in the oil belt, which spring normally masks the filling inlets 326 and thereby closes them. This spring is formed or provided with two nipples 334 which lie diametrically opposite one another and enter into the inlet holes 326, and thereby hold the valve member against angular movement around the longitudinal axis of the tappet, and keep the valve member in position in the guide member 302. The stem 314 of the female member 308 is provided with flats 336 at opposite sides of it, as shown most clearly in Figure 8. These flats enable the end portions of the spring 332 to be flexed inwards until the nipples 334 slide to such a position in the tappet guide 302 that they register with the filling inlets 326 and can snap into them. The resilient valve member 332 can be withdrawn by a reverse operation, when the wedging action between the nipples and the filling inlets flex the spring inwards whilst the tappet is being withdrawn from its guide.

This valve member 332 performs the same functions as the valve member 298 described above with reference to Figure 6, but instead of being controlled by a spring 246 it is itself resilient, and tends to seat itself and close the inlet holes 326. When the fluid pressure in the oil gallery 330 exceeds that in the pressure chamber

268, the valve member 332 will be unseated and admit oil from the oil gallery by way of the said connecting means 326, 280, 282 to the pressure chamber 268. After being unseated, and during the return movement of the valve member 332 onto its seats at the inlet holes 326, opportunity is afforded for a short space of time for oil to leak from the pressure chamber back to the oil gallery. The amount of such leakage will be determined by the resiliency of the spring 332 constituting the valve member. By removing one such spring and replacing it by another spring having one or more different characteristics, such as a different degree of resilience, the leakage permitted from the tappet to the liquid-supply system can be controlled. Instead of two inlet holes 326, only one or more than two may in some cases be provided.

The part 304 of the guide member is of larger diameter than the part 302, and is seated on a shoulder at 338 formed in the cylinder block 306. This arrangement facilitates the assembly of the tappet 300 and its guide member in the cylinder block, and the removal of the tappet when it is desired to substitute one valve member 332 for another.

In each of the tappet assemblies described above, provision is made for restricted leakage from the pressure chamber in the tappet by means which are independent of the fit of the male telescopic member in the female member, and in each construction that restricted leakage is adjustable. Moreover, owing to each of these telescopic members being provided with leakage-preventing annular grooves situated at or towards the opposite ends of the tappet, with or without piston rings or like packing means in the grooves, the main chamber in each tappet is shut off from the atmosphere, and the term "non-atmospheric" applied to the tappets described above refers to this feature, which distinguishes them from tappets of the type described proposed heretofore, in which the flow of oil issuing from the tappets was unrestricted towards the atmosphere at one or both ends of the tappet guide. Such a non-atmospheric tappet is self-priming, and should any air collect, or tend to collect in any part of the internal main chamber within the tappet, such air will be automatically expelled when the tappet is operating in any position, except the constructions shown in Figures 1 and 2, whose use is particularly applicable to engines in which the longitudinal axis of the tappets lies in a horizontal plane, or at any other angular position provided the male member of the tappet operates at a higher level than the female member.

Various modifications may be made in the details of construction described above without departing from the invention. For example, when a tappet, such as the tappet 140 shown in Figure 2, tappet 260 shown in Figure 6, or tappet 300 shown in Figure 7, comprises an internal spring tending to elongate the tappet by forcing its telescopic members apart, which spring supplements the oil pressure in the oil gallery, the self-starting pressure tank 120 and the check valve 104 may be dispensed with, when the oil pressure in the oil gallery is not adequate to operate the tappets. Moreover the invention is not limited to oil-operated tappets, provided that the component parts, particularly the diameters of the telescopic members, are correctly proportioned to cope with the loads against which they have to operate and to suit the viscosity and other char-

acteristics of other liquids which are suitable to satisfy specific requirements.

I claim:

1. A tappet assembly comprising a tappet of the character described having two telescopic members that define a pressure chamber of variable size adapted to contain a liquid, and are movable one in relation to the other for determining the length of the tappet, one of which members constitutes the body of the tappet, and the other of which members constitutes a piston movable axially in relation thereto, restricted leakage of liquid from the pressure chamber being permitted, in combination with a fixed tappet guide member that has an inlet port for supplying liquid under pressure to the pressure chamber for elongating the tappet, leakage-control means for controlling the restricted leakage from the pressure chamber independently of the fit of the piston in the body, and thereby controlling the operation of the tappet, and means situated at opposite sides of said inlet port for preventing liquid from escaping to atmosphere at the ends of the tappet by way of the joint between the tappet and the guide member, whereby the tappet is non-atmospheric and self-priming in any working position.

2. A tappet assembly as set forth in claim 1, wherein the said means is constructed and arranged so as to permit the escape into the atmosphere of air from within the tappet by way of said joint.

3. A tappet assembly comprising a tappet of the character described having two telescopic members that define a pressure chamber of variable size adapted to contain a liquid, and are movable one in relation to the other for determining the length of the tappet, one of which members constitutes the body of the tappet, and the other of which members constitutes a piston movable axially in relation thereto, restricted leakage of liquid from the pressure chamber being permitted, in combination with a fixed tappet guide member, liquid-supply means arranged to supply liquid from an external source of supply under pressure by way of an inlet port in the guide member to the pressure chamber for elongating the tappet, and leakage-control means for controlling and adjusting the restricted leakage from the pressure chamber independently of the fit of the piston in the body, and thereby controlling the operation of the tappet, which leakage-control means comprises a non-return valve device that is associated with said liquid-supply means, and is situated externally of the tappet in said guide member.

4. A tappet assembly comprising a tappet of the character described having two telescopic members that define a pressure chamber of variable size adapted to contain a liquid, and are movable one in relation to the other for determining the length of the tappet, one of which members constitutes the body of the tappet, and the other of which members constitutes a piston movable axially in relation thereto, a restricted escape of liquid from the pressure chamber being permitted, in combination with a fixed tappet

guide member, liquid-supply means comprising a conduit that is arranged to supply liquid from an external source of supply under pressure by way of an inlet port in the guide member to the pressure chamber for elongating the tappet, and leakage-control means for controlling and adjusting the restricted leakage from the pressure chamber independently of the fit of the piston in the body, and thereby controlling the operation of the tappet, which leakage-control means is arranged to return escaped liquid to said conduit.

5. A tappet assembly as set forth in claim 4, wherein the liquid-supply conduit is provided with a non-return valve device that is carried by the guide member at the inlet port and controls the flow of liquid through the same.

6. A tappet assembly as set forth in claim 4, wherein the leakage-control means comprises a valve device arranged to return the escaped liquid to said conduit, and the liquid-supply conduit is provided with a non-return valve device that is carried by the guide member at the inlet port, which valve devices are combined to form an unitary structure.

7. A tappet assembly comprising a tappet of the character described having two telescopic members that define a pressure chamber of variable size adapted to contain a liquid, and are movable one in relation to the other for determining the length of the tappet, one of which members constitutes the body of the tappet, and the other of which members constitutes a piston movable axially in relation thereto, restricted leakage of liquid from the pressure chamber being permitted, in combination with a fixed tappet guide member, liquid-supply means arranged to supply liquid from an external source of supply under pressure by way of an inlet port in the guide member to the pressure chamber for elongating the tappet, and leakage-control means for controlling and adjusting the restricted leakage from the pressure chamber independently of the fit of the piston in the body, and thereby controlling the operation of the tappet, which leakage-control means comprises a valve device having a valve member that controls the flow of liquid through said port and permits the escape of liquid through it when the valve member is moving in a direction away from the tappet.

8. A tappet assembly as set forth in claim 4, wherein the liquid supply conduit is provided with a non-return valve device that is carried by the guide member at the inlet port and controls the flow of liquid through the same, which valve device comprises two seats and has a valve member movable with play between the seats.

9. A tappet assembly as set forth in claim 4, wherein the liquid-supply conduit is provided with a non-return valve device that is carried by the guide member at the inlet port and controls the flow of liquid through the same, which leakage control valve device is constituted by a resilient valve member in the form of a leaf spring arranged to be readily removed, and to be replaced by one having different characteristics.

ARTHUR BURTON BUCKLEY.
